UNITED STATES PATENT OFFICE.

RALPH J. MILLER, OF MADISON, WISCONSIN, ASSIGNEE TO GISHOLT MACHINE COMPANY, OF MADISON, WISCONSIN, A CORPORATION OF WISCONSIN.

IRONING MACHINE.

Application filed March 3, 1923. Serial No. 622,466.

To all whom it may concern:

Be it known that I, RALPH J. MILLER, a citizen of the United States, residing at Madison, in the county of Dane and State 5 of Wisconsin, have invented certain new and useful Improvements in Ironing Machines, of which the following is a specification.

This invention pertains to ironing machines or mangles of the well-known type which is characterized by the provision of a rotating cloth-covered roller or drum, and a shoe having a polished concave face co-operating with the surface of the roller or 10 drum to effect the ironing operation, the roller and drum being so mounted as to be capable of a relative opening and closing movement.

One object of the present invention is to 20 provide a very simple and relatively inexpensive machine of this type characterized by light weight, relatively few parts, and simplicity and efficiency of operation. More specific objects are, to provide an improved mounting and operating mechanism for the shoe, through which the latter can be both separated from the roll to a limited extent and immediately returned to working position under spring pressure, and also 25 separated from the roll and automatically held in separated position, when required, to prevent danger of burning the covering of the roll; to provide an improved mounting for the shoe which may be operated to 30 shift the shoe relatively to the roll by either a hand lever or a foot lever; to provide a mounting for the shoe which, through superior flexibility, will permit the latter more readily to adjust or adapt its working 35 face to the surface of the roll; to provide a shoe mounting which will permit the shoe, when retracted from the roll, to be manually tipped so as to bring its working face uppermost to facilitate the cleaning and wax- 40 ing of the latter; and to provide a shoe mounting and operating mechanism especially adaptable to machines having a comparatively narrow ironing width capacity.

Other objects and attendant advantages 45 of the invention will be apparent to persons skilled in the art from a perusal of the following detailed description, taken in connection with the accompanying drawings, in which I have illustrated one practical and

operative embodiment of the principle of 55 the invention, and wherein—

Fig. 1 is a front elevation of the complete machine, broken out between its ends;

Fig. 2 is a side elevation of the same, 60 viewed from the left of Fig. 1;

Fig. 3 is an enlarged side elevation of the shoe mounting and shoe operating mechanism viewed from the right of Fig. 1, and showing the parts in the relative positions which they assume when the shoe is in 65 working engagement with the roll;

Fig. 4 is a view similar to Fig. 3, but showing the parts in the relative positions which they occupy when the shoe is separated from the roll by the foot lever;

Fig. 5 is a view similar to Fig. 4 showing the relative positions of the parts when the shoe is separated from the roll by the hand lever; this view also showing in dotted lines 70 the upwardly tilted position of the shoe for cleaning and waxing;

Fig. 6 is a detail side elevation of the handle bar socket piece and lower arm of the toggle continuous therewith;

Fig. 7 is a cross section on the line 7—7 80 of Fig. 6;

Fig. 8 is a detail elevation of the lengthwise adjustable upper link of the toggle;

Fig. 9 is a detail front elevation of an H-shaped link; and

Fig. 10 is a side elevation of Fig. 9.

Referring to the drawings, 9 designates each of a pair of lower side frame members connected and spaced at their lower ends by front and rear tie rods 10 and 11. 90 Supported on and connecting the upper ends of the frame members 9 is a board 12. Supported on and bolted to the end portions of the board 12 are right and left upper frame members 13 and 14 formed with 95 bearing bosses 15 in and between which is journaled the spindle 16 of the ironing roller or drum 17.

18 designates an electric motor disposed between the front and rear legs of the upper frame member 13 with its armature shaft extending in a front and rear direction. The motor is disposed in inverted position, and suspended from lugs on the frame member 13, as follows. The feet 19 on the inner side of the motor frame are bolted to the under side of a horizontal strip 20, this latter having upstanding hinge lugs 21 on its

upper side that are pivotally jointed by pivot bolts 22 to a pair of hinge lugs 23 on the inner side of the frame member 13. The feet 24 on the outer side of the motor frame are hung by bolts 25 and nuts 26 from a laterally projecting lug 27 on the outer side of the frame member 13. Coil compression springs 25' encircle the bolts 25, pressing the feet 24 of the motor against the nuts 26. By loosening the latter, slack in the driving belt, hereinafter referred to, can be readily taken up. On the armature shaft of the motor is a small pulley 28, which, through a belt 29, drives a large pulley 30 fast on the outer end of a horizontal transmission shaft 31 journaled in a bearing boss 32 formed on the rear wall of the upper box-like portion of the frame member 13. The inner end of this shaft 31 carries a worm 33 meshing with a worm wheel 34 fast on the drum shaft or spindle, by which the drum is rotated at a proper speed. The pulleys and belt are enclosed in a housing 35, and the hollow upper portion of the frame member 13 containing the shaft, worm and worm gear, is covered by a detachable lid 36 to facilitate access for oiling the gears. Mounted on the front of the frame member 13 is a suitably insulated switch 37 for turning the current onto and off the motor.

Referring next to the shoe, and the manner of, and means for, mounting, heating and operating the same, 38 designates the shoe as a whole possessing the usual form and structure of shoes used in machines of this type, including the longitudinal gas burner pipe 39 mounted therein and equipped at one end with an elbow nozzle 40 for connection to a gas supply pipe or hose. This shoe, however, instead of being supported at its ends, as usual, is mounted at a point substantially coincident with its longitudinal center and in a manner which enables it to move bodily toward and from the drum and also to rock on a longitudinal pivot axis. Mounted on the board 12 at its longitudinal center is a bracket comprising parallel side plates 41 formed with base attachment flanges 42 apertured to receive fastening bolts 43, a connecting and spacing web 44, and horizontal bearings 45 on the upper ends of the side plates 41. In the bearings 45 is mounted a pivot shaft 46. Pivoted at its lower end on shaft 46 is an H-shaped link 47 shown in isolated detail in Figs. 9 and 10, the upper end of which is pivotally connected to the shoe by central hinge lugs 48 on the back of the latter and a hinge bolt 49. Mounted on the pivot shaft 46, between the lower limbs of the H-shaped link 47, is a bell-crank lever 50, having the principal functions of a toggle abutment and a support for the lower edge of the shoe when the latter is moved out of contact with

the drum by either the hand lever, or the foot lever hereinafter described. This bell-crank 50 has a rearwardly projecting arm 51, a forwardly projecting arm 52 lying beneath and crosswise of the lower edge of the shoe, and a downwardly extending arm 53 lying behind the web 44 of the bracket. On the rear face of the H-shaped link 47 are a pair of spaced lugs 54, 54' (Fig. 10), one of which 54' is longer than the other for a purpose later disclosed. Pivoted to and between the lugs 54, 54' at its upper end is the upper arm of a toggle, said upper arm preferably made adjustable as to length by being composed of two members 55 and 56 (Fig. 8), one having a tenon 56' screwing into a tapped hole 55' in the other. The lower arm of the toggle, as shown in the detail views Figs. 6 and 7, comprises a pair of parallel strips 57 rigidly connected by an integral strip 58, which latter is continued upwardly and terminates in a handle socket 59 adapted to receive a removable handle 60. The two strips 57 of the lower toggle arm at their lower end straddle and are pivotally connected by a pin 61 to the horizontal arm 51 of the bell-crank 50, and at their upper end straddle and are pivotally connected by a pin 62 to the lower end of the lower member 56 of the upper toggle arm.

The depending arm 53 of the bell-crank 50 is normally drawn rearwardly toward the web 44 of the bracket by a thrust spring 63 encircling a tension bolt 64 mounted in the arm 53 and extending rearwardly through an opening 65 in the web 44, said spring bearing at one end against a nut 66 on the bolt, by which its tension may be adjusted, and at its other end on the web 44.

67 is a pedal lever fulcrumed at 68 on the rear tie-rod 11 and connected a short distance in advance of its fulcrum by hinged links 69 and 70 to the longer rearwardly projecting hinge-lug or arm 54' of the H-shaped link 47. A brace 71 is interposed between the rear tie-rod 11, adjacent to the lever fulcrum point 68, and the board 12 to prevent bending of the tie rod.

Supported on brackets 72 carried by the upper frame members 13 and 14 is the usual ironing board 73; and detachably suspended by hooks 74 engaged in holes in the lower side frame members 10 is a pan 75 for supporting long articles like sheets and table-cloths as the latter are fed over the front edge of the board 73.

By reference to Fig. 2 it will be observed that the roll and shoe are of what is known as the "open end" type of construction. That is to say, the arc-shaped working area of the shoe and drum at one end of the machine (the left as herein shown) is open and unobstructed by the upper side frame member or any shoe support, so that it is possible to iron pieces of somewhat greater width

than the length of the roll and shoe by passing the piece once through the machine and then turning the same edge for edge and re-passing it through the machine to iron the part overhanging the open end of the roll and shoe during the first passage. This feature is of special convenience in machines having a comparatively narrow width capacity for ironing, such as that herein shown and described. It may here be further mentioned that the shoe supporting and controlling mechanism herein described and shown is best adapted to machines of comparatively narrow width capacity, since it is somewhat impractical to support a long shoe at a single point midlength thereof.

The mode of operating the machine should be fairly well understood from the foregoing description of its structural features. Figs. 1, 2 and 3 illustrate the normal working position of the parts wherein the shoe is pressed against the roll by the spring 63 acting through the elbow lever 50, the straightened toggle, and the H link 47. By depression of the foot lever 67, the link 47 is swung outwardly on its pivot 46, as shown in Fig. 4, thus retracting the shoe from the roll, the lower edge of the shoe resting on the arm 52. As soon as the foot is removed from the pedal lever 67, the spring 63 immediately returns the parts to the working position.

If it is desired to retract the shoe from the roll and hold it in retracted position for some time, to prevent danger of burning the covering of the roll or for any other reasons, the hand lever 60 is swung rearwardly to the position shown in Fig. 5. This it will be observed breaks the toggle, so that the spring 63 no longer acts to restore the shoe to working position, and the shoe is thus held separated from the roll, resting on the arm 52. If at this time it is desired to clean or wax the concave working face of the shoe, the latter is readily tilted by manual manipulation to the dotted line position shown in Fig. 5, which facilitates these operations. The parts are restored to normal working position by merely drawing the hand lever 60 forwardly again, which straightens the toggle. From the foregoing it will be observed that while the foot and hand levers have a function in common to the extent of separating the shoe from the roll, yet they also have differing functions in that the foot lever merely effects a temporary and limited retraction of the shoe and when released allows the spring to return the shoe to working position, while the hand lever permanently separates the shoe from the roll until it is again returned to its normal upright position.

While I have herein shown and described one practical embodiment of the invention which has been found in practice to satis-

factorily effectuate the stated purposes and objects thereof, it is manifest that the machine may be variously modified in details of structure and arrangement without departing from the fundamental principles of operation or sacrificing any of the advantages inherent therein. Hence I reserve such variations and modifications as fall within the spirit and purview of the appended claims.

I claim—

1. In an ironing machine, the combination of a frame, an ironing roll journaled at both ends in and lengthwise of said frame, a shoe behind and co-operating with said roll, a single rigid link pivotally supported at its lower end on said frame and pivotally jointed at its upper end to and mid-length of the back of said shoe, spring actuated means for pressing said shoe into contact with said roll, and a hand lever connected to said link and extending above said roll and shoe for swinging said link rearwardly and thereby drawing said shoe away from said roll.

2. In an ironing machine, the combination of a frame, an ironing roll journaled in said frame, a shoe co-operating with said roll, a central hinge lug on the back of said shoe, a rigid link pivotally supported at its lower end on said frame, a hinge bolt pivotally connecting said hinge lug to the upper end of said link, a hand lever pivotally supported at its lower end, a link connecting said hand lever to said first-named link, and spring-actuated means on which said hand lever is pivotally supported operative through said hand lever and links to press said shoe into contact with said roll.

3. In an ironing machine, the combination of a frame, an ironing roll journaled in said frame, a shoe co-operating with said roll, a link pivotally supported at its lower end on said frame and at its upper end pivotally jointed to the back of said shoe mid-length of the latter, means for swinging said link rearwardly to thereby withdraw said shoe from said roll, and a member underlying said shoe and formed with a flat upper surface extending transversely of the full width of the lower edge of said shoe serving to support the latter when retracted from the roll.

4. In an ironing machine, the combination of a frame, an ironing roll journaled in said frame, a shoe, a substantially vertical link pivotally supported at its lower end on said frame and at its upper end pivotally jointed to the back of said shoe, a rearwardly extending arm on said link, a lever fulcrumed coaxially with the lower pivot of said link, a toggle pivoted at its upper end to said arm and at its lower end to one arm of said lever, a spring anchored to and acting upon the other arm of said lever, an upwardly extending handle continuous with

- the lower arm of said toggle, a foot lever fulcrumed on said frame, and a link connecting said foot lever to the rearwardly extending arm of said link.
5. In an ironing machine, the combination of a frame, an ironing roll journaled in said frame, a shoe, a substantially vertical link pivotally supported at its lower end on said frame and at its upper end pivotally jointed to the back of said shoe mid-length of the latter, a rearwardly extending arm on said link, a three-arm lever fulcrumed coaxially with the lower pivot of said link and having a rearwardly extending arm, a for- wardly extending arm underlying the lower edge of said shoe, and a depending arm, a toggle pivoted at its upper end to the rearwardly extending arm of said link and at its lower end to the rearwardly extending arm of said three-arm lever, a spring anchored to and acting upon the depending arm of said three-arm lever, an upwardly extending handle on the lower arm of said toggle, a foot lever fulcrumed on said frame, and a pull link connecting said foot lever to the rearwardly extending arm of said link.
- 10

RALPH J. MILLER.
